FIG. 6

TIG-Z

A technical drawing of a cylindrical component. At the top, there are four small rectangular cutouts. The front face of the cylinder has several horizontal lines. Numbered callouts point to specific features: '51' and '50' point to the top edge; '49' points to a vertical slot on the front face; '48' points to the right edge; '16' points to a small circular feature on the left; '51' and '50' point to the bottom edge; and '34' points to a feature on the left side. Below the cylinder, the word 'Inventors' is written in a cursive script, followed by the names 'Louis F. Klipstein' and 'John U. Barr,' both in a cursive script.

UNITED STATES PATENT OFFICE.

LOUIS F. KLIPSTEIN AND JOHN U. BARR, OF NEW ORLEANS, LOUISIANA.

MOP-WIRING MACHINE.

Application filed June 28, 1926. Serial No. 119,193.

This invention relates to a machine for wire binding mops and the like, and has for its primary object to provide a machine of the class specified embodying convenient instrumentalities for facilitating the securing 5 of mop strands to the handle by means of a wire binder that is duplicated in its application, or applied to the inner and outer portions of the mop head, whereby a reliable fastening for mop strands relatively to a 10 handle is effected.

A further object of the invention is to provide a machine of the class specified embodying readily controllable instrumentalities for feeding a wire strand and first effecting the formation of a terminal hook and subsequently an interlocking hook conjointly acting with the terminal hook after the wire binder has been properly tensioned with relation to the part of the mop head to which 20 it is applied.

A still further object of the invention is to generally improve machines of this character by comprising in the organization 25 thereof wire feeding, clamping, bending and severing means, conveniently actuated and under the control of an operator, to facilitate the positive application of a binding wire to a mop head.

With the foregoing and other objects and advantages in view, the invention consists 30 in the construction and arrangement of the several parts which will be more fully hereinafter described and claimed.

In the drawings:

Fig. 1 is a side elevation of a machine, partially broken away and embodying the features of the invention.

Fig. 2 is a front elevation of the same, partially broken away.

Fig. 3 is an enlarged sectional side elevation of a portion of the machine, illustrating in full and dotted lines the operation of the several parts.

Fig. 4 is a horizontal section on an enlarged scale, showing the rack and pinion and part of the gearing for operating the same to control the movement of the wire clamp, together with the upper stop or check 45 and intermediate operating means for the said clamp, to respectively effect a clamping action and a release of the wire during certain steps of the operation.

Fig. 5 is a horizontal section on an enlarged scale, taken below the wire clamp 55 means and particularly showing the bend-

ing mechanism, a portion of the table of the machine being illustrated together with the upright frame mounted thereon.

Fig. 6 is a horizontal section on an enlarged scale of a portion of the wire cutting mechanism.

Fig. 7 is an end elevation of the cutter, showing a wire extending over the cutting edge in dotted lines.

Fig. 8 is a plan view of a portion of the cutter, showing the wire in horizontal section.

Figs. 9 and 10 are sectional elevations of the mop fiber and handle broken away, to 70 show the manner of securing the head of the mop to the handle.

The numeral 5 designates a bed or table of suitable dimensions and having a slot 5^a extending inwardly from the front edge 75 thereof a suitable distance. The bed or table 5 has supporting legs 6 connected by transverse braces 7. Rising from the rear portion of the bed or table 5 is a vertical frame consisting of parallel spaced uprights 8 having bracket plates 9 secured to the front and rear sides thereof and provided with lower flanges 10 bolted or otherwise secured to the bed or table 5. Extending forwardly from the vertical frame between the uprights 80 8 are upper intermediate and lower supporting arms 11, 12 and 13, each essentially comprising parallel plates or strips 11^a. On the upper end of the vertical frame a wire guide is mounted, comprising radially disposed arms 14 having rollers 15 in their outer extremities, between which the wire 85 16 is passed for regularly feeding downwardly over the front portion of the machine. The parallel plates or strips 11^a of the arms 11, 12 and 13 embrace and are secured to an upright fixed guide shaft 17, 90 which terminates at its upper end coincidentally with the upper edges of the plates or strips 11^a of the upper arm 11 and at its 95 lower extremity coincidentally with the lower edges of the plates 11^a of the lower arm 13. On the left sides of the arms 12 and 13 a guide rod or strip 18 is secured and thereon is adjustably mounted a check 19 and a trip 100 20, the said check and trip being held in their adjusted positions by rear set-screws 21 and 22 which bind against the rear edge of the guide rod or strip 18. The check 19 projects forwardly and has a downwardly 105 directed, angular terminal 23, the lower edge 24 of said check being horizontally straight.

65

80

105

110

The trip 20 has a slideable trip nose 25 mounted in the forward extremity thereof and provided with a downwardly tapered face 26, for convenience in passing the same. 5 The trip nose 20 has a pin 22 extending therethrough and engaging opposed slots 28 in the sides of the forwardly projecting extremity of the said trip, a spring 8 being mounted in the rear of the trip nose 25 within 10 in the trip 20 so as to always maintain said trip nose in normal forwardly projected position.

A clamp is mounted on the lower arm 13 below the trip 20, the said clamp consisting 15 of a forwardly projecting arm 29 having a slot 30 extending through the forward end thereof and communicating with a vertical bore 31 located at a distance inwardly from the outer end of the said arm 29. Extending transversely through the outer end of the arm 29 is a shaft 32 having a cam 33 fixed thereon and operating in the slot 30, the left-hand end of the said shaft 32 projecting outwardly beyond the adjacent side of the 25 arm 29 and having a trip wheel 34^a fixed thereon and formed with radial arms 35 adapted to be struck by the trip nose 26 and the forward angular depending end 23 of the check 19. The cam 33 is clearly 30 shown in side elevation by Fig. 3 and is eccentrically mounted so as to project the greater portion thereof at one side of the shaft 32. Within the bore 31 a clamping means is mounted and consists of two semi-cylindrical clamping members 34 held in 35 place by a lower tubular screw nut 35, the said members 34 having opposing grooves 36 in their straight sides. The clamping members 34 are shiftable, one towards the other, within the bore 31, the upper part of the said bore being reduced, as at 37, and in alinement with an upwardly projecting guide tube 38, extending to and through a 40 projection or block 39, which is disposed above the arm 12 and has a bore 40 extending vertically through the inner extremity thereof, in which the upper end of the tube 38 is secured. The projection or block 39 has its rear end attached to the upper extremity of a rack 41 with teeth 42 in its rear edge, the lower end of the said rack being secured to the rear end of the arm 29 of the 45 clamping means.

Depending from the lower side of the inner extremity of the lower arm 13 is an angular guide foot 43, which is held in fixed position by securement to the said arm 13 and has at its inner end a vertical guide bore 44 and a horizontally disposed die block 45. Rising from the inwardly projecting horizontal member 43^a of the foot 43 and in alinement with the bore 44 is a short vertical guide tube 46, with which the lower side of the tubular nut 35 is adapted to register when the clamping arm 29 is lowered, 50

as indicated in dotted lines by Fig. 3. A cutter bore 47 extends rearwardly through the rear side of the horizontal member 43 to the guide bore 44, and in this bore 47 is a cylindrical cutter 48 of the form shown on an enlarged scale by Figs. 6, 7 and 8. The forward end of the cutter 48 is forwardly reduced by equally tapering the upper and lower sides 49 thereof between guards 50 having front blunt ends 51 adapted to bear 75 against the inner end of the die 45 and prevent the cutting edge 49^a of the cutter from being crushed or dulled by forceful contact with the said rear edge of the cutting die. The cutting die is removably held in the 80 forward extremity of the horizontal member 43^a of the foot 43 by a wedge pin 45^a, as clearly shown by Fig. 6. The bore 44 continues down into a slotted guard 52 formed as a part of the lower side of the horizontal 85 member 43^a of the angular foot 43, to facilitate removal of the severed portions of the wire in a downward direction and also to assist in producing a hooked terminal at the upper extremity of the severed portion of 90 the wire depending from the said horizontal member 43^a. A block or boss member 53 is secured to the rear side of the angular foot 43 close to and below the lower edge of the lower arm 13, the said block being provided 95 with a rearwardly projecting fulcrum support 54 in which is intermediately fulcrumed a link 55 having a lower extremity depending below the said support 54 and connected to a head 56, in which the rear end of the 100 cutter 48 is secured, as shown by Fig. 3. The upper extremity of the link 55 is connected to the forward end of a coupling link 57, which in turn has its rear end attached to the lower portion of an operating 105 lever 58, fulcrumed at its lower end to the arm 13, the upper end of the lever 58 being provided with a handle or grip 59.

Below the wire cutting mechanism a suitable distance and mounted in forward and 110 rear bearings 60 and 61 is a rotatable and longitudinally slideable rod or stem 62, having attached to its rear end at a suitable distance from the rear edges of the uprights 8 an angular counterbalancing arm 63. The bearing 60 rises from the table or bed 5 in advance of and centrally disposed with relation to the space between the uprights 8, and the bearing 61 is mounted and held between the said uprights adjacent to the front 115 edges of the latter. The rod or stem 62 continues in advance of the bearing 60 and has an upwardly diverging or flaring slot 64 at its front free end extending downwardly to a horizontal web 65, the slot 64 having outwardly curved upper edges 66. The lower extremity of the wire from the horizontal member 43^a of the foot 43 immediately above the position of the rod or stem 62 is inserted downwardly in the slot 64. On the 120

rod or stem 62 at a proper distance is fixed a cam sleeve or cylinder 67, having therein a spiral groove 68 and provided at opposite ends with flanges 69 and 70, to respectively 5 bear against the rear side of the forward bearing 60 and the front side of the adjacent bracket plate 9, the latter and the rear similar plate being vertically slotted as at 9^a to permit the rod or stem 62 to 10 operatively pass therethrough. A slide collar 71 is mounted on the cam sleeve or cylinder 67, and in an upper, vertically extending opening 72 thereof is mounted a screw-threaded plug 73 having a depending pin 74, which is 15 always held projected in the spiral or cam groove 68 of the said cam sleeve or cylinder. Secured to the upper portion of the slide collar 71 is the forward end of an operating rod 75, which extends through an opening 20 76 in the upper portion of the rear bearing 61 and has free sliding action in an upward and rearward direction in the said bearing. The rod 75 passes through the upper portion 25 of the slot 9^a in the front bracket plate 9, and to the rear end of the said rod 75 the forward end of a link 77 is pivoted, the rear end of said link being also pivoted to the lower arm 78 of an operating lever 79 fulcrumed in a bracket 80 secured to the rear 30 portions of the uprights 8. The levers 58 and 79 respectively have springs 58^a and 79^a attached at one end of each to said levers, the forward extremity of the spring 58^a being secured to the arm 13 and the upper extremity of the lever 79^a being secured to one of the uprights 8. The lever 79 has a grip or handle 81 at its upper end for convenience in operating the same. The rod or stem 62 with the operating mechanism therefor as just explained constitutes the wire bending mechanism which functions in the formation of the hooked loop at the lower end of the wire, as shown in dotted lines by Fig. 3, and also assists in properly guiding the wire.

Mounted in suitable bearings 82, one of which is clearly shown by Fig. 2, secured to or between the legs 6, is a shaft 83 on which is mounted a treadle wheel consisting of opposed heads 84 connected at regular intervals by rods 85.

The heads have radial arms 84^a extending from central webs 84^b to the peripheral rings 84^c thereof, and the said treadle ring 55 or wheel 84 is free for forward and rearward, partial rotary movement with the shaft 83 either through pressure of the foot or pulling and pushing action of the hands of an operator. However, this is but one 60 convenient means for operating the shaft 83, and in some instances it may be desirable to actuate the said shaft through readily controllable power means to which the shaft 65 may be connected. A vertical shaft 88 is mounted in a lower bearing bracket 89 se-

cured to the one cross brace 7 and also through an upper bearing projection 90 connected to the upper arm 12. The shaft 88 has a beveled gear 91 on its lower end which is held in continual mesh with a beveled pinion 92 fixed on the shaft 83 adjacent to the said gear, and on the upper extremity of the said shaft 88 is fixed a beveled pinion 93, held in mesh with a beveled gear 94 on a transverse shaft 95, extending through the members 11^a of the upper arm 12, the said shaft 95 having a pinion 96 fixed thereto and rotatable therewith and held in continual mesh with the teeth 42 of the rack 41 for raising and lowering the upper guide 39 and the arm 29 of the wire clamping mechanism including the shaft 32 and cam 33 which cooperates with the clamping members 34. By means of this mechanism the parts of the improved machine just referred to may be readily controlled as to their elevated and lowered positions during the several steps of feeding and applying the wire to mop heads and sticks or handles.

Preliminary to threading the wire 16 through the parts of the machine, the adjustably mounted check 19 is positioned at a height required to permit enough wire to be carried down for application to the mop handle and strands and to insure that the wire will be in an expanded condition. The wire 16, from a suitable source of supply such as a reel located adjacent the machine, is then threaded between the rollers 15 of the arms 14 and passed down through the projection or block 39 into the tube 38, between the clamping members 34 and downwardly through the tube 46 and then through the bore 44 and also into the forward slot 65 of the working extremity of the spindle or stem 62 of the bending mechanism, when said stem has been projected into operative position as shown by Fig. 3. The spindle or stem 62 is disposed as shown by Fig. 3, by first moving the lever 79 from the extreme forward position shown in dotted lines by Fig. 3 to the second or full line position, this latter movement of the lever bringing the lower extremity 78 forwardly and through the link 77 likewise moving the rod 75, which acts on the collar 71 and pushes the cylinder having the cam groove 68 with the said spindle forwardly until the front flange 69 of the cylinder strikes the rear side of the bearing 60. During this movement of the cylinder 67 and spindle 62 through the medium of the collar 71, the pin 74 simply has a forward pushing operation, in view of the fact that there is no resistance to the sliding movement of the cylinder with the groove 68 until the front flange 69 engages the bearing 60 as just specified, and as a consequence the upwardly diverging slot 64 and horizontal web 65 will be directly under and in proper alinement

with the bore 44 of the cutter mechanism above. The lower extremity of the wire threaded through the parts of the machine will also be passed into the slot 64 a sufficient distance to form a hook on the lower end of the wire. The lever 79 is then pushed from the full line position shown in Fig. 3 in a rearward direction until it reaches the maximum rear position thereof 10 as shown by dotted lines in Fig. 3, this further movement of the lever 79 causing the collar 71 to slide forwardly over the cam cylinder 67, in view of the fact that the limit of forward adjustment of said cylinder will 15 be reached when the flange 69 thereof engages the rear side of the bearing 60. This further movement of the lever, therefore, causes the collar 71 to slide forwardly and the pin 74 to move in the cam groove 68 and 20 partially rotate the cylinder 67 and cause the spindle 62 to similarly rotate and bend the lower extremity of the wire 16 to form the hook 16^a, as shown in dotted lines by Fig. 3. During this rotation of the spindle 25 62, the angular arm or counterbalancing device 63 is elevated, and after detachment of the hook from the forward working end of the said spindle, the latter is reversely rotated by the gravitating movement of the 30 angular arm or counterbalancing device 63, and the pin 74 moves in a reverse direction in the cam groove 68 of the cylinder 67 and at the same time the groove 64 at the forward extremity of the spindle 62 is restored 35 to normal position ready for a succeeding similar operation, or the formation of a hook on the lower extremity of the wire. After the hook 16^a has been formed on the lower extremity of the wire, the lever is 40 pulled forwardly a sufficient distance to cause the collar 71 to engage the rear flange 70 and move said cylinder rearwardly and the spindle 62 in a similar rearward direction to clear the table directly under the bore 44 in the horizontal member 43^a of the foot 43. The handle *h* with the mop strands *m* applied thereto as shown by Fig. 9 is 45 then brought in position over the slot 5^a of the table 5 and the lower portion of the wire with the hook extremity is looped around the mop strands close to and above the usual pin or nail *n* driven through the end portion of the handle, and the hook 16^a caught around the wire above the handle 50 and mop strands as shown by Fig. 1. The treadle wheel comprising the opposed heads 44 connected at regular intervals by the rods 85 is then kicked forward by the operator and the clamping means including the 55 clamping members 34 is moved upwardly a sufficient distance above the upper end of the tube 46 to draw the wire taut and at the same time the partially secured mop strands are elevated with the handle, the upward 60 movement of the clamping means being ef-

fected through the rack bar 41 by the gearing including the vertical shaft 88, as heretofore explained. The clamping mechanism is then moved to a higher position for actuation by the trip nose 25, which engages one 70 of the arms 35 to release the clamping members 34 as shown in the upper dotted position of the clamping means in Fig. 3. This further upward movement of the clamping means permits the wire to slacken and the 75 operator gives the partially secured mop strands and mop handle a short upward movement, which produces a second hook 16^b in interlocking relation to the hook 16^a, as shown by dotted lines in Figs. 9 and 10, and the wire immediately above the second 80 formed hook 16^b is severed by operating the cutting mechanism including the cylindrical cutter 48 and the die 45 through the medium of the lever 58, which is forced rearwardly 85 against the resistance of the spring 58^a. After the wire is severed, the mop strands and handle are removed and the two interlocking hooks 16^a and 16^b given a sharp blow 90 with a hammer, to complete the inside fastening of the mop strands. It will be understood that when the lever 58 is released, the spring 58^a will return the same to normal position and draw or slide the cylindrical cutter 48 rearwardly into normal position to 95 clear the bore 44 for subsequent movement therethrough of the wire 16, as in the preliminary threading of the wire hereinbefore explained, when the mechanism will then be 100 in condition for a repetition of the same operation. After the mop strands at the head thereof have been partially secured to the mop handle above the pin or nail *n*, securing 105 of the said strands is completed by turning the same over the inner wire fastening loop *l* as shown by Fig. 10, and an outer wire loop *l'* is applied over the upper or head end of the strands below the pin or nail *n*, to thereby prevent slipping of the 110 mop head on the handle 6. A number of the mop strands and handles may be first primarily assembled as shown by Fig. 9 and subsequently the mop strands will be 115 turned over the adjacent lower end of the handle *h* and each secured by the outer loop *l'* by the same operation heretofore explained in connection with applying the inner loop *l*. When the mechanism is arranged for each succeeding operation, or to 120 apply the wire loops relatively to the mop head extremity of the mop strands, the lower treadle wheel including the heads 84 and connecting rods 85 will be moved in a forward direction to lower the clamping members 34 and move the rack bar 41 downwardly through the mechanism heretofore described and properly dispose the wire through the tube 46 and angular foot 43. When the arm 29 of the clamping means is 125 elevated its full extent, the upper edge 130

thereof contracts with the lower straight edge 24 of the check 19 and the outer depending angular end or terminal 23 of the said check engages one of the arms 35 of the wheel 34^a to cause the clamping members 34 to tightly engage or grip the wire passed therebetween.

What is claimed as new is:

1. In a machine for wire binding mops and the like, a work table, an upright frame held by the table and including supporting means, wire feeding and clamping means a rack connecting the wire feeding and clamping means for uniform vertical movement, wire cutting means, a shiftable bending mechanism below the wire cutting means, and cam and interrelated mechanism for operating the said several instrumentalities at timed intervals.
2. In a machine for wire binding mops and the like, a work table, an upright frame held by the table and including supporting means, wire feeding and clamping means in superposed spaced relation and connected for uniform vertical movement, means for connecting the feeding and clamping means for unitary reciprocating movement, wire cutting means below the feeding and clamping means, a horizontally shiftable bending and guide mechanism below the wire cutting means, and mechanism for operating the said instrumentalities.
3. In a machine for wire binding mops and the like, a work table, an upright frame held by the table and including supporting means, spaced wire feeding and clamping means having uniform vertical movement, a rack connecting said feeding and clamping means, wire cutting means having a guide bore therethrough and also provided with a sliding cutter in part movable across the said bore, a shiftable bending and guide mechanism below the wire cutting means, and mechanism for operating the several instrumentalities.
4. A machine for wire binding mops and the like, comprising a work table having wire-engaging elements disposed in vertical sequence thereover and consisting of wire feeding and clamping means and wire cutting and bending and associated guiding instrumentalities, the wire feeding and clamping means being uniformly vertically movable and the wire cutting and bending instrumentalities held in fixed position relatively to the said feeding and clamping means, a rack connecting the wire feeding and clamping means, and mechanism for operating the several instrumentalities.
5. A machine for wire binding mops and the like, comprising a work table, wire feeding and clamping means disposed in spaced relation, a rack connecting said feeding and clamping means for unitary movement, and wire cutting and slotted bending and guid-

ing means below the feeding and clamping means, and mechanism for operating the said rack and also the cutting and bending and guiding means.

6. A machine for wire binding mops and the like, comprising a slotted work table, wire feeding and clamping means in spaced relation and connected for uniform vertical reciprocating movement, the clamping means having a rotatable device projecting exteriorly thereof together with a cam operated by the latter device and clamping members operable by the cam, wire cutting means, bending and guiding means respectively including a slidable cutter and spindle and a slidable yieldable guide, the spindle being provided with a bending slot at its forward end between the spindle and the guiding means for passage of the wire therethrough, and mechanism for operating the said instrumentalities including trip and check devices to cooperate with the wheel of the clamping means.

7. A machine for wire binding mops and the like, comprising a work table, upper wire feeding means, clamping means below the wire feeding means and also acting as a feeding means and connected to the said upper wire feeding means for uniform vertical movement, the clamping means including movable clamping members, a transverse shaft carrying a cam to operate the said members and an exterior wheel having radial arms, normally fixed but shiftable trip and check means to engage the arms of said wheel, wire cutting and bending and guiding means disposed below the clamping means and held in fixed vertical position relatively to the said clamping means, and mechanism for operating the said instrumentalities.

8. In a machine for wire binding mops and the like, a work table, wire feeding and clamping means, wire cutting means, bending means including a forwardly and rearwardly slidable and rotatable spindle having a front slotted end, and mechanism for operating the said instrumentalities.

9. A machine for wire binding mops and the like, comprising a work table, a frame held by and extending above the said table and having supporting means at various elevations thereon together with a vertical fixed shaft, spaced wire feeding and clamping means having a rack connecting and operating the same for unitary movement, said feeding and clamping means engaging the said shaft, trip and check devices for cooperation with the said clamping means, wire cutting and bending and guiding means below the clamping means, and mechanism for operating the said instrumentalities.

10. A machine of the class specified, comprising wire feeding means, wire clamping means connected to and spaced from the

wire feeding means and having an exteriorly located projecting rotary operating device, wire cutting means, trip and check devices for engagement with the said exteriorly located said rotary operating device of the clamping means and which are normally fixed but adjustable to modify the stroke of the wire feeding and clamping means, wire bending means below the cutting means, and mechanism for operating the several instrumentalities.

11. A machine of the class specified, comprising a work table having a slot opening out through the front portion thereof, 15 an upright frame held on the table and provided with supporting means disposed in spaced relation, wire feeding and clamping means vertically movable with relation to the upright and including a guide tube held 20 on the clamping means and extending through the guide means, a wire cutting means below the clamping means and also supporting a wire guiding tube, bending mechanism below the wire cutting mechanism 25 having the main bending element thereof longitudinally shiftable forwardly and rearwardly and also rotatable and having a wire bending slotted structure at its forward extremity, and mechanism for operating the several instrumentalities.

12. A machine of the class specified, comprising a slotted work table, an upright frame held by the said table and having supporting means projecting forwardly 35 therefrom, a fixed guiding shaft held by the said supporting means, wire feeding and clamping means having a rack connecting the same for unitary vertical reciprocation and mounted to move relatively to the said fixed shaft, check and trip devices, said clamping means having a rotary projection which is engaged by the check and trip devices for operating the clamping means to alternately release and dispose the latter in 40 clamping relation to a wire, a wire cutting and guiding means below the clamping means, and mechanism for operating the several instrumentalities.

13. In a machine for wire binding mops and the like, a work table, wire feeding and 50 clamping means, wire cutting means, bending means including a forwardly and rearwardly slideable and rotatable spindle having an upwardly flared slot in its front end, gravitating means secured to the rear 55 end of the said spindle to restore the latter to normal position, and mechanism for operating the said instrumentalities.

14. In a machine for wire binding mops and the like, a work table, wire feeding and 60 clamping means connected for unitary movement, wire cutting means below the feeding and clamping means, bending means below the cutting means and including a forwardly and rearwardly slideable 65 and rotatable spindle having a front extremity constructed with an upwardly flaring slot in its front end to receive and bend a wire into hook shape, means cooperating with said spindle to longitudinally shift the 70 same and also impart a rotating movement thereto, balancing means connected to the rear end of the spindle for restoring it to normal position, and mechanism for operating the said instrumentalities. 75

15. A machine of the class specified, comprising wire feeding means, wire clamping means connected to and spaced from a part of the wire feeding means and having clamping members and actuating cam 80 therefor with an exteriorly located rotary operating device, vertically adjustable trip and check devices for engagement with the said exteriorly located rotary operating device of the clamping means for respectively 85 releasing and tightening the same, wire cutting means below the clamping means, longitudinally shiftable and rotatable wire bending means below the cutting means, and mechanism for operating the several instrumentalities. 90

In testimony whereof we have hereunto set our hands.

LOUIS F. KLIPSTEIN.
JOHN U. BARR.
